JAR

Edward F. Raymond, Huntington Park, Calif., as
signor to John Grant, Los Angeles, Calif.

Application April 4, 1936, Serial No. 72,752

12 Claims. (Cl. 255—27)

This invention has reference to jars used in rotary well drilling, and is principally concerned with improvements in mechanisms for adjusting the jar parts while the tool is lowered in the well, 5 to vary and control the force of the jarring blow. Generally speaking, the effect of such jar adjustments is to vary the resistance to releasing movement of the parts in the course of the jarring operation, and thereby to vary the pull load required to trip the jar, and the magnitude of the 10 blow delivered by the jar.

The present type of jar is similar to other jars in the respect that it operates by relative longitudinal movement between the body and mandrel 15 portions to deliver the jarring blow, and contains a detent mechanism which holds the body and mandrel against relative movement in the jarring direction, until a predetermined pull is taken on the drill pipe string. The present detent mechanism includes a pair of releasably engaging members, one of which is adjustable relative to the other to vary the pull load required to disengage them and thereby trip the jar. In accordance 20 with the invention in its preferred form, such adjustment of the adjustable detent member is accomplished by relative rotation between the body and mandrel, the direction of adjustment of the detent being controllable by selective movement of the drill string from the ground surface.

30 It is believed that all the various features and objects of the invention can be understood most readily and to best advantage, from the following detailed description of certain illustrative forms of the invention shown in the accompanying drawings. It is to be understood, however, that these illustrations are typical only, and that various changes and modifications may be made without departure from the intended spirit and scope of the invention.

40 In the drawings:

Figs. 1 and 2 are vertically continuing views, partly in section, showing a typical form of jar embodying the invention;

Fig. 3 is a longitudinal and partly sectional view showing the jar parts in changed positions;

Fig. 4 is a view similar to Fig. 3 illustrating the jar parts in released condition;

Figs. 5 and 6 are fragmentary views illustrating certain adjustment positions of the mandrel relative to the body;

Fig. 7 is a section on line 7—7 of Fig. 2;

Figs. 8, 9, 10 and 11 are cross sections taken on the correspondingly numbered lines of Figs. 3 and 4.

55 Figs. 12 and 13 are fragmentary sectional views

illustrating a variational form of detent mechanism; and

Figs. 14 and 15 are horizontal sections on lines 14—14 and 15—15 of Fig. 12.

Referring first to Figs. 1 and 2, the jar may be 5 described generally as comprising telescopically movable body and mandrel sections 20 and 21, and a detent mechanism, generally denoted at 22, adapted to hold the mandrel against upward movement relative to the body until a predetermined pull load is imposed on the drill string. 10 The body 20 comprises a tubular section 23 into the upper end of which is threaded the pin 24 of a clutch member 25. The lower end of the body has a threaded connection at 26 with the pin end 15 27 of a pipe or sub 28 that is connected with the drill bit, fishing tool, or other tools in conjunction with which rotary jars are customarily used.

The mandrel 21 includes an intermediate tubular portion 29 having its upper end threaded at 20 30 into the box end of a coupling or second clutch member 31, the upper pin end 32 of which is threaded at 33 into the box end of the drill pipe 34. The lower end of mandrel section 29 is connected at 35 with a sleeve 36 which carries the 25 adjustment lugs to which I later refer. The upward jarring impact is communicated from the mandrel to the body by the engagement of shoulder 37 on the mandrel enlargement 38, with shoulder 39 on the lower end of pin 24. Circulating 30 fluid is conducted through the jar from the drill pipe 34 into the bore of member 28 attached to the lower end of the body, by a wash pipe 40 which is threaded at 41 into the bore of coupling 31 to move with the mandrel in its vertical 35 travel. Fluid leakage around the wash pipe and through the coupling bore, is prevented by a suitable packing gland as indicated at 42. The bottom portion of the wash pipe extends through a packing gland 43 within pin 27, and has sliding engagement with the packing as the pipe 40 travels with the mandrel with relation to the body.

The detent mechanism at 22 comprises a split sleeve 44 carried on the mandrel and confined 45 by a pair of adjustable nuts 45 and 46. As best illustrated in Fig. 2, the upper and lower ends of sleeve 44 are confined within ferrules 45a and 46a in the opposing ends of nuts 45 and 46, so that by adjusting one nut relative to the other (the 50 threads 47 and 48 on the mandrel both being left-handed) the pressure on the ends of the sleeve is varied to regulate the effective diameter of the sleeve, all in the manner to be presently described. As best illustrated in Figs. 3 and 4, 55

the sleeve is divided into vertically extending, radially contractible segments or detents 44a, by slotting the sleeve longitudinally and intermediate its ends as indicated at 50.

- 5 The exterior configuration of the sleeve presents, in effect, an annular upwardly facing shoulder 51 which engages the downwardly facing body shoulder 52 to releasably hold the mandrel against upward movement relative to the body. 10 As shown in Fig. 2, each portion 44a of the sleeve between slots 50, is shaped to provide a bowed detent spaced at 53 from the mandrel and radially contractible by the wedging engagement between shoulders 51 and 52 by the exertion of a 15 predetermined upward pull on the mandrel.

During drilling operations, the mandrel and body are locked against relative rotation by the clutch 54 comprising a series of interfitting teeth 55 and 56 formed on the upper and lower ends of 20 body and mandrel members 25 and 31, respectively. In carrying out the jarring operation, the drill string first is raised to bring the mandrel and body shoulders 51 and 52 into engagement as shown in Fig. 3. The detent mechanism 22, and 25 specifically the sleeve 44, is set to impose a predetermined resistance to movement of the sleeve shoulder 51 past body shoulder 52, by the relative adjustment of nuts 45 and 46, as will later appear more fully. When a sufficient upward 30 pull is exerted via the drill string to overcome this resistance, sleeve 44 becomes radially constricted about the mandrel by the wedging engagement between shoulders 51 and 52, to the extent that the sleeve suddenly disengages from the body 35 shoulder and releases the mandrel for upward movement to the position of Fig. 4. Upward travel of the mandrel is arrested by the impact of the shoulder 37 against the body shoulder 39 to deliver an upward jarring blow.

40 In order to reset the jar for continued drilling or a subsequent jarring operation, the drill string is lowered straight down, moving the mandrel from the position of Fig. 4 to the positions of Fig. 1 or 3, and forcing the detent sleeve 44 downwardly within the body until shoulders 51 and 52 are positioned for reengagement. It will be noted that the angularities of the bowed detent surfaces 44b and body surface 58 are small as compared with the angularities of shoulders 51 and 52, and that the wedging action of bowed surface 58 tending to constrict the detent sleeve during its downward relative movement, is correspondingly gradual. As a result, substantially less force is required to constrict the detent sleeve in the 55 reseating operation than that required to release the detent mechanism in the jarring operation.

The driller frequently finds that the blow being delivered by the jar either is too heavy or too light to suit the requirements of the particular 60 job for which the tool is being used. Consequently, it is desirable to incorporate in the jar, means for adjusting the detent mechanism to control its resistance to release, and therefore the magnitude of the jarring blow, and to provide an adjustment means that can be regulated without having to remove the jar from the well. In the 65 illustrated preferred form of the invention, I provide a detent adjustment that operates by virtue of relative rotation between the body and mandrel, to vary the radial spread of the slotted detent sleeve 44. By reason of the flexibility of the bowed sleeve segments 44a, the maximum diameter of the sleeve at the outer extremity or 70 detent shoulder 51, may be regulated by subjecting the sleeve to variable endwise pressure. Such

endwise pressure is applied to the sleeve by nuts 45 and 46, and the adjustment is accomplished by selectively rotating these nuts in the manner now to be explained.

As shown in Fig. 9, each of the mandrel nuts 5 has four circularly arranged and equally spaced ways 59. Referring to Figs. 3 to 5, the body 23 carries two pairs of diametrically opposed splines 60 and 61 positioned in vertical alignment above and below the body detent shoulder 52. In the 10 relative positions of the body and mandrel shown in Figs. 2 and 7, splines 61 are received within one pair of the diametrically opposed ways 59 in nut 46 to hold the latter against rotation relative to the body. In the position of the parts shown in 15 Fig. 4, body splines 60 similarly extend within ways 59 in nut 45 to key the latter to the body. In order to reduce the spread of the detent sleeve and thereby reduce its resistance to disengagement from the body shoulder 52 during the jar- 20 ring operation, the drill string is rotated to turn the mandrel 29 in a clockwise direction, as indicated by the arrow in Fig. 4, and to turn the mandrel within nut 45 which at the time is held against rotation by body spline 60. During this 25 adjustment, nut 45 is backed away from the sleeve to reduce its endwise compression. The opposite or sleeve spreading adjustment is made with the parts in the position shown in Fig. 3. By rotating the mandrel with nut 46 held against rotation by 30 body spline 61, the nut travels upwardly on the mandrel to longitudinally compress the sleeve and increase the bow in the sleeve segments 44a.

For the purpose of avoiding over-adjustment of the detent mechanism and to enable the driller 35 to know exactly the degree of adjustment effected in a single adjusting operation, I limit the permissible relative rotation between the mandrel and body during the course of each single adjustment, but yet enable as many successive 40 adjustments to be made as may be desired. In other words, the extent of each individual adjustment is predetermined, but any number of successive adjustments may be made until the 45 detent mechanism imposes just the right resistance to release.

Sleeve 36 on the lower end of the mandrel carries a pair of lugs 63 spaced 180° apart, and a second pair of lugs 64, offset vertically and spaced 90° with relation to lugs 63, see Fig. 11. 50 The body 23 carries two vertically aligned pairs of spline-shaped lugs 65 and 66; also a similarly shaped lug 67 positioned between and in vertical alignment with one pair of the vertically aligned lugs 65 and 66. The spaces at 68 and 69 between the aligned lugs 65, 67 and 66 are of sufficient length to pass lugs 63 and 64 during rotation of the mandrel.

Assuming first that it is desired to adjust nut 46 on the mandrel in the manner previously explained, the mandrel is raised from the position of Fig. 2 a distance sufficient to release clutch 54 and to bring lug 64 (at the left in Fig. 2) opposite or in horizontal alignment with space 69. The drill string and mandrel are then rotated in the direction of the arrow, turning the mandrel within nut 46 until the lower lugs 63 come into engagement with body shoulders 66, as shown in Fig. 2. In this single adjustment operation, nut 46 will have become turned 90° relative to the mandrel. If it is desired to make a second adjustment of nut 46 in the same direction, the mandrel is raised from the position of Fig. 3 to bring lug 63 at the left, opposite space 70 69 as shown in Fig. 5, and the mandrel then 75

rotated to bring lug 64 appearing on the foreside of the mandrel, into engagement with body shoulder 67, thereby limiting the adjustment travel to 90° as before. As will be apparent from the foregoing, any number of successive 90° adjustments of nut 46 can be made simply by lowering and raising the mandrel to allow lugs 63 to clear space 69, the vertical offset of the lug limiting each adjustment.

Assume now that it is desired to adjust the upper mandrel nut 45 with the parts shown in the position of Fig. 4, and nut 45 engaged by splines 60. The mandrel first is lowered to bring lugs 64 opposite space 68, and the mandrel then rotated in the direction of the arrow until further turning is arrested by the engagement of one of the lugs 63 with body shoulder 67. A successive adjustment may then be made by raising the mandrel until lug 63 is brought opposite space 68 as shown in Fig. 6 and the mandrel then turned until its rotation is arrested by the engagement of lugs 64 with body shoulders 65. Repeated similar adjustments are made by alternately lowering and raising the mandrel, and then rotating, to cause lugs 63 and 64 to alternately clear space 69.

All of the above described adjustments are made by rotating the drill string to the right, as viewed from the top; the advantage being that the rotation is in the direction tending to keep the pipe joint tight. In case locked-joint pipe is being used, adjustments may be made by oppositely rotating the drill string and mandrel, as will be apparent from the preceding description without necessity for further explanation.

In Figs. 12 to 15 I show a variational form of detent mechanism that, while generally similar to the previously described form, differs in the construction of the sleeve assembly. Here the mandrel carried detents, generally indicated at 70, include a plurality of circularly arranged, bowed individual detent members 71, the upper and lower ends of which seat within the longitudinal mandrel grooves 78. As shown in the vertical sectional view of Fig. 13, each of the individual detents 71 is spaced at 72 from the mandrel to be capable of inward pressure relative thereto, and has an angular shoulder 73 adapted to engage a body shoulder 74 of corresponding angularity. In this form of the invention, the body includes two sections 75 and 76 threadedly connected at 77, shoulder 74 being formed on the lower end of the upper body section pin end 75a. The ends 71a and 72a of the bowed detents 55 are confined within ferrules 79 in the ends of nuts 45' and 46', the detent compressive force of the nuts being taken by a pair of metallic washers 80 bearing against the ends of the individual detents 71.

I claim:

1. In a rotary jar including a body and a relatively longitudinally movable mandrel, both supported on a drill pipe, and striking shoulders on said body and mandrel adapted to impact to deliver the jarring blow, the combination comprising, radially adjustable means carried by said mandrel for releasably holding the body and mandrel against relative movement in a jarring direction, and means for making successive radial adjustments of said holding means while the jar is lowered in the well, the last mentioned means including stops confining each individual adjustment within a predetermined limit.

2. In a rotary jar including a body and a relatively longitudinally movable mandrel, both sup-

ported on a drill pipe, and striking shoulders on said body and mandrel adapted to impact to deliver the jarring blow, the combination comprising, radially adjustable means carried by said mandrel for releasably holding the body and 5 mandrel against relative movement in a jarring direction, and means operated by successive rotational and vertical movements of the drill pipe for making successive radial adjustments of said holding means while the jar is lowered in the 10 well, the last mentioned means including means confining each individual adjustment within a predetermined limit.

3. In a rotary jar including a body and a relatively longitudinally and rotatably movable mandrel, both supported on a drill pipe, and striking shoulders on said body and mandrel adapted to impact to deliver the jarring blow, the combination comprising, radially adjustable means carried by said mandrel for releasably holding the 15 body and mandrel against relative movement in a jarring direction, and means for making successive radial adjustments of said holding means while the jar is lowered in the well, the last mentioned means comprising lugs carried on the body 20 and mandrel and selectively engageable to arrest relative rotation of the body and mandrel at different positions.

4. In a rotary jar including a body and a relatively longitudinally and rotatably movable mandrel, both supported on a drill pipe, and striking shoulders on said body and mandrel adapted to impact to deliver the jarring blow, the combination comprising, radially adjustable means carried by the mandrel for releasably holding the 30 body and mandrel against relative movement in a jarring direction, and means for making successive radial adjustments of said holding means while the jar is lowered in the well, the last mentioned means comprising lugs carried on the body 35 and mandrel and selectively engageable by vertical movement of the drill pipe to arrest relative rotation of the body and mandrel at different positions.

5. In a rotary jar including a body and a relatively longitudinally movable mandrel, both supported on a drill pipe, and striking shoulders on said body and mandrel adapted to impact to deliver the jarring blow, the combination comprising, radially adjustable means carried by said 45 mandrel for releasably holding the body and mandrel against relative movement in a jarring direction, said holding means being radially adjustable by differential pressures applied to it longitudinally of the mandrel, and means for 50 radially adjusting said holding means while the jar is lowered in the well, by rotation of said drill pipe.

6. In a rotary jar including a body and a relatively longitudinally movable mandrel, both supported on a drill pipe, and striking shoulders on said body and mandrel adapted to impact to deliver the jarring blow, the combination comprising, radially adjustable means for releasably holding the body and mandrel against relative 65 movement in a jarring direction, said holding means being radially adjustable by differential pressures applied to it longitudinally of the mandrel, and means for radially adjusting said holding means while the jar is lowered in the well, by rotation of said drill pipe.

7. In a rotary jar including a body and a relatively longitudinally movable mandrel, both supported on a drill pipe, and striking shoulders on said body and mandrel adapted to impact to de- 75

liver the jarring blow, the combination comprising adjustable means holding the body and mandrel against relative movement in a jarring direction, and means for making successive adjustments of said holding means while the jar is lowered in the well by successive relative rotational and vertical movements of the body and mandrel, the last mentioned means including stops confining each individual adjustment with-
10 in a predetermined limit.

8. In a rotary jar including a body and a relatively longitudinally movable mandrel, both supported on a drill pipe, and striking shoulders on said body and mandrel adapted to impact to deliver the jarring blow, the combination comprising radially adjustable means holding the body and mandrel against relative movement in a jarring direction, and means for radially adjusting said holding means; and last mentioned means including a pair of relatively movable members bearing on opposite ends of said holding means.

9. In a rotary jar including a body and a relatively longitudinally movable mandrel, both supported on a drill pipe, and striking shoulders on said body and mandrel adapted to impact to deliver the jarring blow; the combination comprising radially adjustable means carried on said mandrel and holding the body and mandrel against relative movement in a jarring direction, and means for radially adjusting said holding means, the last mentioned means including a pair of nuts threaded on the mandrel and bearing against opposite ends of said holding means.

10. In a rotary jar including a body and a relatively longitudinally movable mandrel, both supported on a drill pipe, and striking shoulders on said body and mandrel adapted to impact to deliver the jarring blow; the combination comprising radially adjustable means carried on said mandrel and holding the body and mandrel against relative movement in a jarring direction, and means for radially adjusting said holding means, the last mentioned means including a

pair of nuts threaded on the mandrel and bearing against opposite ends of said holding means, and means on said body for selectively engaging said nuts to rotate them on the mandrel.

11. In a rotary jar including a body and a relatively longitudinally and rotatably movable mandrel, both supported on a drill pipe, and striking shoulders on said body and mandrel adapted to impact to deliver the jarring blow; the combination comprising a plurality of circularly arranged 10 detents carried by said mandrel and engaging the body to hold the mandrel and body against relative movement in a jarring direction, detent adjusting means including a pair of nuts threaded on the mandrel and engaging the ends of said 15 detents, means on said body for selectively engaging said nuts to rotate them and thereby apply to the detents a variable pressure that determines their radial positions, and means for arresting relative rotation between the body and 20 mandrel at predetermined intervals while one of said nuts is engaged by the last mentioned means.

12. In a rotary jar including a body and a relatively longitudinally and rotatably movable mandrel, body supported on a drill pipe, and 25 striking shoulders on said body and mandrel adapted to impact to deliver the jarring blow; the combination comprising a plurality of circularly arranged detents carried by said mandrel and engaging the body to hold the mandrel and 30 body against relative movement in a jarring direction, detent adjusting means including a pair of nuts threaded on the mandrel and engaging the ends of said detents, means on said body for 35 selectively engaging said nuts to rotate them and thereby apply to the detents a variable pressure that determines their radial positions, and lugs carried on the body and mandrel and selectively engageable by relative vertical movement of the body and mandrel to arrest relative rotation of 40 the body and mandrel at different positions.

EDWARD F. RAYMOND.
